PORTABLE BOAT

Phillip L. Crisp, Marion, N. C.

Application January 7, 1950, Serial No. 137,461

1 Claim. (Cl. 114—123)

1

The present invention relates to boats, and more particularly has reference to a portable self-propelled boat which is highly stable in use, thereby providing a boat which finds particular application for sporting purposes such as fishing, racing and the like.

Heretofore, it has been proposed to provide water vehicles wherein the boat body has been stably supported to prevent accidental overturning of the boat, together with pedal-operated means for imparting the necessary propulsion to the boat. However, these prior assemblies have been relatively complex in structural detail and have not been especially suitable for fishing purposes.

An object of the present invention is to provide a boat of the character described wherein the body of the boat is provided with pontoons adjustably supported by the boat whereby the pontoons may be folded to a nested position relative to the boat body to permit ease of transportation and facilitate storage of the boat.

A further object of the invention is to provide a self-propelled boat wherein a pedal-operated drive connection is employed for imparting the necessary movement to the propeller, and a seat structure carried by the boat is adjustable relative to the pedal-operated member.

Another object of the invention is to provide a foldable portable boat for sporting purposes which can be easily and quickly folded for transportation purposes and made ready for operation in a minimum of time without the necessity of employing skilled help or requiring the use of numerous tools.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 is a plan view of the present invention.

Figure 2 is a fragmental plan view showing the manner in which the pontoons are swingably mounted to the hull.

Figure 3 is a view in side elevation, partly broken away, of the construction shown in Figure 1.

Figure 4 is a fragmental side elevational view, partly in section, showing propellers and the connections therefor.

2

Figure 5 is a front view of the boat shown in Figure 1 with pontoons shown in adjusted positions by the broken lines.

Figure 6 is a detail view showing the pivotal connection between the hull and the pontoon supporting arm.

Referring to Figure 1, I have shown a hull 10 having a flat stern 11 and an arcuate bow 12 which is curved downwardly, as at 13, merging with a flat hull bottom 14. The hull may be wood, metal or any other suitable material. The hull 10 is stabilized by means of a pair of pontoons 15 supported on opposite sides of the hull by connecting elements denoted generally 16.

15 A seat structure 17 is supported by the gunwales of the hull preferably adjacent the stern, and a pedal-operated unit 18 is employed to impart movement to propellers 19 and 20, and a rudder 21 is detachably supported by the stern of the boat, for the usual purposes.

20 The pontoons 15 may be of any desirable type and since each pontoon and its associated elements is similar in structural detail, the following description will be confined to a single pontoon. A pair of spaced support plates 22 are conveniently attached to the side of the hull 10, and one leaf of a hinge 23 is attached to the upper end of the plate 22, while the other leaf is secured to the lower face of an arm 24, the inner end of the arm being adapted to rest upon the gunwale of the hull when the arm is in the horizontal position as shown by the full lines in Figure 5. A pair of spaced ears 25 are provided on the plate 22 near the lower end thereof, and a similar pair of ears 26 are carried by the lower face of the arm 24 intermediate the ends of the arm. A link 27 is pivoted to the ears 25 as shown at 28, and a link 29 having an elongated slot 30 is pivoted to the ears 26, as shown at 31. A bolt and wing nut assembly 32 pivotally connects the links 27 and 29, and by positioning the links in alignment (Figure 5) and by drawing up the wing nut, it will be appreciated that the arm 24 will be fastly supported in the horizontal position. On the other hand, by releasing the nut and bolt assembly, the pivotal connection between the links may be broken to enable the arm and as a consequence the pontoon to be moved downwardly relative to the hull, as will later be more fully described.

45 The outer end of each arm 24 is pivotally connected to an elongated link 33 by an adjusting device 34, the opposite end of the link 33 being provided with a swivel 35 which is mounted in 50 a swivel plate 36 mounted on the upper surface

of the pontoon 15. A wing nut or other locking device 37 cooperates with the swivel and swivel plate 35 to lock the link 33 against pivotal movement. Manifestly, with the links 33 at right angles to the arms 24, the pontoons 15 will be firmly supported relative to the hull in the position shown in the full lines in Figures 2 and 5. If it is desired, however, the pontoons may be moved to a position at somewhat greater distance beyond the sides of the hull by manipulating the locking devices 34 and 37 so that the pontoons may be swung about the point of pivot of the links 33 to the arms 24, as indicated in the broken lines in the above mentioned figures. To enable the pontoons to be folded to a nested position with respect to the hull 10, the pivot between the links 27 and 29 is broken whereupon the arms 24 and the pontoons may be moved to the broken line location in Figure 5, whereby the arms will be substantially parallel to the sides of the hull with the pontoons located beneath the bottom of the hull. The boat may, of course, be very easily transported in this condition and will require considerably less room for storage purposes.

The seat structure 17 comprises a suitable tubular framework 38 and each end of the framework has a pair of downturned legs 39 and the downturned legs 39 are adapted to fit into sockets or seats 40 provided at spaced intervals along each gunwale of the hull, and a suitable locking device 41 is provided for each forward leg 39. An arm and back harness 42 is attached to the gunwales of the hull by a ring structure 43 forwardly of the seat and the harness is provided with buckles 44 to enable it to be adjusted for the particular user of the boat.

The pedal-operated unit 18 comprises an upstanding supporting bracket 45 in which the shaft of the pedals 46 is journaled. A sprocket 47 is carried by the pedal shaft and a chain 48 is trained around the sprocket 47 and a smaller sprocket 49 carried by the shaft 50 which is journaled in a bracket 51. A gear 52 is supported by the shaft 50 and meshes with a second gear 53 mounted on the upper end of shaft 54. The shaft 54, as indicated in Figure 3, extends downwardly through the bottom 14 of the boat at an angle relative to the bottom through a downwardly depending fin or keel-like member 55. The outer end of the shaft 54 extends through a suitable packing 56 to prevent the admission of water into the hull 10.

A bracket 57 depends downwardly from the bottom of the hull of the boat and has spaced arms 58 and 59, the arm 59 being angularly disposed with respect to the arm 58. The propeller 19, preferably of the three-blade type, is carried by a shaft 54, the shaft 54 being rotatably mounted in the arm 59. The shaft 54 is coupled to a horizontally extending fitting 61 by means of a universal joint 62 of any suitable type and shaft 63 which supports the propeller 19 is operably connected with the fitting 61. The fitting 61 comprises a body having an enlarged recess 64 and a rectangular opening 65 extends inwardly from the base of the recess. The shaft 63 is provided with a ball 66 and the end of the shaft is squared, as shown at 67, the squared portion 67 being adapted to enter the rectangular opening 65. Manifestly, as long as the shaft 54 is turned, it will be appreciated that the fitting 61 will likewise be rotated by virtue of the universal joint 62, but with the shaft 63 in the position shown in Figure 4, the shaft will not be rotated. However, if the shaft is moved to a position

whereby the squared extension 67 is within the opening 65, the shaft and the propeller 19 will rotate simultaneously with the shaft 54.

In order to move the shaft 63 longitudinally, the shaft is provided with a bearing 68 which will enable the shaft to turn but will prevent lengthwise displacement of the shaft. An arm 69 extends upwardly from the bearing 68 and downturned end 70 of a connecting rod 71 is pivotally connected to the arm, as shown at 72. The rod 71 is journaled in bearings 73 attached to the bottom 14 of the hull 10. The rod 71 is provided with a control lever 74 which is parallel to the side of the hull, and the lever cooperates with a notched plate 75 supported by the side of the hull adjacent the seat 17. By placing the lever 74 in the desired notch, the lever and its associated parts will be locked in that particular position. Manifestly, to move the squared extension 67 into the recess 65, movement of the lever in the proper direction will swing the downturned end 70 toward the bow of the hull and this movement will be imparted to the arm 69, whereupon the shaft 63 will be moved forwardly, thus connecting the shaft 63 with the fitting 61. The lever is then locked in this position and both propellers will turn so long as pedals are operated. To disengage the propeller 19, the lever is swung in the opposite direction whereupon the shaft 63 will assume the position shown in Figure 4 and the fitting 61 will rotate independently of the shaft 63.

The operation of the boat may be briefly summarized as follows:

33 The boat is normally transported to the water body with the pontoons in the position shown by the dotted lines in Figure 5 and, before launching, the arms 24 are moved upwardly about the pivots, and the arms are maintained in the horizontal position by tightening the bolt and wing nut unit 32 when the links 27 and 29 are in alignment. When the pontoons have been moved to the desired location relative to the side of the hull, the adjusting devices 34 are tightened to thus maintain the pontoons in the desired position.

34 The operator then sits in the seat with the harness in proper position and by operating the pedals 46 a propeller 19 will be rotated through the drive connection between the pedals and the propeller. If it is desired to also employ the propeller 20, the control lever 74 is manipulated so as to move the shaft 63 to a position where the extension 67 is lodged in the recess 65 and consequently the propeller 20 will be moved in unison with the propeller 19. Of course the movement of the lever 74 in the opposite direction will disconnect the propeller from the coupling and the fitting 61 will turn independently of the propeller shaft 63.

60 The rudder 21 includes a blade 76 of any suitable design, the blade being attached to a vertical rod or the like 77. The rod 77 has an integral horizontally extending portion 78 which terminates in a control element 79. As shown in Figure 3, a notched bar 80 extends transversely of the hull and conveniently attached at its ends to the gunwale. By disposing the horizontal portion 78 in one of the notches in the bar, the rudder will be maintained in that position. The rod 77 is mounted to the stern of the boat for vertical pivotal movement by means of upper and lower clamps 81 and 82, respectively, the clamps being of the type which can be readily attached to or disconnected from the stern.

75 It will be appreciated, therefore, that I have

5

provided a portable boat structure which is very stable, thereby making the boat especially adaptable for fishing and the like. Furthermore, the boat may be readily dismantled and assembled by the user, and these operations can be accomplished by merely employing a suitable wrench or wrenches. The boat in its folded or collapsed position may be easily transported and will occupy a minimum of storage space.

I claim:

In a portable boat of the character described, a hull, arms extending outwardly from each side of the hull, a pivotal connection between each arm and the hull whereby each arm may swing from a horizontal position downwardly into substantial parallelism with the side wall of the hull, a hinged brace means cooperating with each arm and the hull to maintain said arms in the horizontal position, a pontoon located on each side of the hull, a link pivoted to the free end of each arm for movement about a vertical axis, a swivel connection between the link

6

and the pontoon, and means cooperating with said pivotal connection between the link and arm to secure said link and pontoon in the desired adjusted position, the position of the link relative to the arm determining the distance between the side wall of the hull and the pontoon.
